UNITED STATES PATENT OFFICE.

WILLIAM GOLDBERG, OF DENVER, COLORADO.

CAMP STOVE.

Application filed July 7, 1927. Serial No. 203,927.

This invention relates to improvements in the construction of camp stoves of the kind that employ gasoline or other liquid fuel.

It is the object of this invention to produce 5 an improved stove of this type which shall be so constructed that the parts remain in fully assembled relation during transportation and which will therefore withstand rough usage. It is a further object to produce 10 a stove that can be conveniently primed and in which neither the burners nor the tank has to be moved during the priming operation. It is a still further object to produce a stove having an improved wind break and another 15 object is to produce a valve mechanism of novel construction by means of which the priming operation can be conveniently controlled.

The above and other objects that may be 20 come apparent as this description proceeds, are attained by means of a construction and an arrangement of parts that will now be described in detail and reference for this purpose will now be had to the accompanying 25 drawings in which the preferred embodiment of the invention has been illustrated and in which:

Fig. 1 is a front elevation of the stove, showing the same;

30 Fig. 2 is a view, partly in section, taken on line 2—2, Fig. 1;

Fig. 3 is a section taken on line 3—3, Fig. 2;

Fig. 4 is a section similar to that shown in 35 Fig. 3 and illustrates a slightly modified construction;

Fig. 5 is a section of the valve taken on line 5—5, Fig. 7;

Fig. 6 is a section taken on line 6—6, Fig. 5;

40 Fig. 7 is a section taken on line 7—7, Fig. 5; Fig. 8 is a view showing a modification of the priming valve construction;

Fig. 9 is a section taken on line 9—9, Fig. 8; and

45 Fig. 10 is a section taken on line 10—10, Fig. 1.

My stove comprises a casing having a bottom 1, a side member 2 and ends 3 and 4. The side opposite side 2 has been indicated by numeral 4 and is lower than the side 2. 50 The ends 3 and 4 are bent so as to provide short portions 5 and 6 which are secured to the side 4 in the manner shown in Fig. 1. Extending longitudinally of the casing and parallel with the sides 2 and 4 is a hollow 55 partition. In Fig. 3 this partition has been shown in cross sections and is formed of a

piece of sheet metal having sides 7 and 8 which are connected at their upper ends in such a way as to form a rabbet 9 that extends the entire length of the partition. The 60 lower ends of sides 7 and 8 are bent outwardly at right angles in the manner indicated by numeral 10 and these ends rest on the upper surface of bottom 1. The bottom of the casing has been pressed upwardly so as to 65 form an elongated narrow ridge 11 whose width is equal to the distance between the sides 7 and 8. This ridge projects upwardly into the partition and provides an obstruction which prevents gasoline from flowing from 70 one side of the partition to the other. Tongues 12 are stamped out of the bottom 1 and are bent over the outwardly projecting flanges 10 so as to hold the partition in place. The ends of the partition members 7 and 8 75 are also provided with outwardly extending flanges 13 which are engaged by tongues 12 in the manner shown in Fig. 3. The ridge 11 is provided with a plurality of openings 14 and the upper end of the partition is provided with a plurality of openings 15 (Figs. 1 and 2). A grate comprises a plurality of U-shaped members 16 which are spotwelded to parallel bars 17 so as to form an assembly 80 like that shown in Fig. 2. This grate is secured to the side 2 by means of hinges 18 and has its opposite side resting in the rabbet 9. Fastened to one of the side members of the U-shaped member located at the left (Fig. 2) 85 is a baffle plate 19. This baffle plate has its center portion cut out so as to form an opening 20 (Fig. 3). The function of this baffle plate will appear as the description proceeds.

Secured to the upper surface of the bottom member 1 is a manifold 21 to each end of 90 which is connected a burner 22. The manifold 21 has a mixing chamber 23 that extends upwardly to a point above and adjacent to the left hand burner (Fig. 2). The burner assembly is secured to the bottom member 1 100 by means of brackets 24.

Between the hollow partition and the side 4 is a chamber within which is located a gasoline tank 25. This tank is held in place by means of a clamp 26, and is provided at 105 one end with a pipe 27. This pipe connects the tank with a valve which has been indicated as a whole by numeral 28. A generator tube 29 has one end connected with the duplex valve 28 and extends over the adjacent burner and terminates in the mixing 110 chamber 23. A valve 30 of ordinary construc-

tion controls the opening through the generator tube 29. Valve handle 31 is connected with the valve stem 32 by means of a universal joint 33, which permits the handle to be swung inwardly into the box or to be moved to the position shown in Fig. 2. The tank 25 is provided with a fill opening 34 which is controlled by means of a plug 35. Tank 25 is adapted to contain gasoline and air under pressure. When the valve 30 is open gasoline will flow from the tank 25 into and through the generator tube 29. When the burner is operating the heat will vaporize the gasoline in the generator tube so that only vapor will enter the mixing chamber 23. Before the stove can be made to function, it is, of course, necessary that the generator tube 29 shall be heated to such a temperature that the gasoline within the same will be converted into vapor. In order to heat the generator tube, I have provided the distributor plate of burner 22 with a priming cup or central depression 36, which is adapted to receive a quantity of gasoline which may be ignited and which serves to heat the generator tube 29.

Difficulty has heretofore been experienced in providing suitable means for conducting gasoline from the tank 25 to the priming cup 36, and it has been customary to have the tank 25 with its attached generator tube detachable from the casing, so that the end of the generator tube can be brought into or above the priming cup 36 in order to deposit gasoline therein. In my construction, the tank 25 is securely fastened to the casing and consequently the generator tube 29 is also stationary. For the purpose of transferring gasoline to the priming cup, I have provided a duplex valve structure which has been indicated as a whole by numeral 28. This duplex valve comprises two valves, one of which has been indicated by numeral 30 and which comprises the valve stem 32. This controls the flow of gasoline from the pipe 27 to the generator tube 29, (Fig. 5). Extending from the opening into which the pipe 27 is secured to the valve which controls the flow of gasoline to the priming tube 37 is an opening 38. This opening terminates underneath the valve seat with which the valve stem 39 operates. This valve stem has a threaded portion 40 (Figs. 6, 7 and 9) and is provided with a handle 41 by means of which it can be rotated so as to open and close the valve. An opening 42 extends from the valve chamber in which the valve stem 39 is located to an opening into which one end of the priming tube 37 is inserted (Fig. 6). When valve stem 39 is rotated so as to open the passage-way from the opening 38 to the opening 42, gasoline will flow from the tank into pipe 37 and into the priming cup 36. After the priming cup has been filled with gasoline valve 39 is closed and the gasoline in the priming

cup ignited. The capacity of the priming cup is such that when the gasoline which it will contain has been consumed, the generator tube 29 will have been heated sufficiently to convert the gasoline therein to vapor and therefore when valve 30 is open, gasoline will pass into the generator tube and become vaporized and flow through the mixing chamber 23 and through the manifold 21 and out through the openings in the distributor plate of the burner. This gaseous mixture will then ignite and burn with a blue flame which will continue to keep the generator tube 29 heated. The flow of gasoline to the burner shown at the right in Fig. 2 is controlled by a valve 43.

In the embodiment shown in Figs. 5 and 6 the pipe 37 has been shown as secured to the duplex valve structure by means of set screw 44. This pipe 37 is therefore stationary and will remain in the position shown in Fig. 2. Owing to the fact that pipe 37 is empty during the burning of the stove, it becomes very highly heated with the result that after long use it has to be replaced by a new one; this can readily be done by loosening the set screw 44 and withdrawing the old pipe.

In Figs. 8 and 9 I have shown a slight modification which is so constructed that the priming tube 37^a which corresponds to the priming tube 37 in the other figures, has its end 45 bent at right angles in the manner shown in Fig. 9. This end projects upwardly through an opening that intersects opening 42 at right angles and is held in place by means of a screw 46. The priming tube 37^a can be rotated from full line to dotted line position, (Fig. 8). When it is in full line position, the hole 47 registers with the opening 42 at right angles and when valve 39 is open gasoline will flow through this tube into the priming cup 36. After sufficient gasoline has been transferred to the priming cup the tube is moved into the dotted line position so as to be out of the zone of the fire and will therefore be kept from becoming heated to such an extent that it will be destroyed.

In Fig. 4 I have indicated a modification in which the hollow partition has been formed integral with the bottom 1. The bottom is folded so as to form the two sides 7^a and 8^a. In other respects this construction is the same as that shown in Fig. 3. I have indicated above that the ridge 11 serves to prevent gasoline from flowing from the burner compartment to the tank compartment. Ordinarily, there will be no gasoline in either of these compartments, but sometimes it happens that the operator is negligent and permits the gasoline to overflow when he fills the priming cup. When this happens, some of the gasoline may flow into the chamber containing the tank and become ignited when the burner is ignited. The

burning of gasoline around and about the tank 25 would have a tendency to raise the temperature to such a high point that an explosion might occur. With the construction shown and described, this danger is obviated.

A cover member 48 is hinged to the upper edge of the side 2 and this member has secured to it three other pieces which have been indicated by numerals 49, 50 and 51. The parts designated as 49 and 50 are secured to the cover by means of hinges 52. When the cover is in open position, the end members 49 and 50 are swung outwardly into the position shown in Figs. 1 and 2 and rest on the projecting fingers 53. The part marked 51 is hinged to the outer edge of the cover and rests upon the upper ends of members 49 and 50 when the parts are in the position shown in Fig. 1. The side 51 is adapted to extend down between the tank and the parts marked 4, 5 and 6, and serves to completely enclose the parts when the cover is moved to closing position. The side 51 is provided with a handle 54 by means of which the stove may be carried. The stove is provided with two legs 55 of a well known construction that serves to support the stove when it is in operative position and which will hold the cover from opening when the parts are folded for transportation.

The parts to which the invention relates in the present application are embodied in the duplex valve construction by means of which the priming cup can be filled with gasoline without moving the tank 25 and in which this valve is also protected from the flame by means of the baffle plate 19. In addition to this the ridge 11 is a feature that is novel in a stove of this type. I also wish to call attention to the assembly comprising the cover member 48 and parts 49, 50 and 51 which form an excellent wind break and in which the part 51 cooperates with the cover

so as to entirely enclose the gasoline tank during transportation. 45

Having described my invention what I claim as new is:

1. A camp stove comprising, in combination, a casing having two ends, two sides and a bottom, the bottom having an upwardly extending ridge extending from one end member to the other, said ridge being parallel to the sides, a hollow partition extending along the ridge so as to divide the casing into two compartments, a burner assembly in one compartment, a fuel tank in the other compartment and a conduit extending from the fuel tank to the burner assembly. 50 55

2. A camp stove of the class described, a casing, a burner assembly within the casing, means for securing the burner assembly in place, a grate supported by the casing, means for supporting the grate above the burner assembly, a fuel conduit extending over a burner of the burner assembly, a valve 60 65 in said conduit and a baffle plate secured to the grate, said plate separating the burner from the valve.

3. A camp stove of the class described, comprising, in combination, a casing having a bottom member, two end members and two sides, one of said sides being lower than the other, a hollow partition extending lengthwise of the casing between the sides so as to divide the casing into two compartments, a fuel tank in the compartment between the partition and the lower side, a burner assembly in the other compartment, means for conducting fuel from the tank to the burner and a cover hinged to the higher side, said cover having a member hinged to its free edge, said hinged member being adapted to cooperate with the lower side to enclose the tank. 70 75 80

In testimony whereof I affix my signature.
WILLIAM GOLDBERG.
